SIZE TAG FOR GARMENT HANGER

Maurice Cohen, 3580 NW. 52nd St.,
Miami, Fla. 33142

Filed May 14, 1973, Ser. No. 359,883

Term of patent 14 years

Int. Cl. D20—99

U.S. Cl. D19—13

FIG. 1

FIG. 2

FIG. 5

FIG. 3

FIG. 6

FIG. 4

FIG. 1 is a perspective view showing my new design for a size tag for a garment hanger;

FIG. 2 is a side elevational view thereof;

FIG. 3 is a top plan view thereof;

FIG. 4 is a bottom plan view thereof;

FIG. 5 is a front elevational view thereof; and

FIG. 6 is a rear elevational view thereof.

The portion of a coat hanger shown in broken lines in FIG. 1 is for illustrative purposes only and forms no part of the claimed design.

I claim:

The ornamental design for a size tag for garment hanger, substantially as shown and described.
